EGG DEHYDRATOR

Charles McLean, Berkeley, Calif.

Application December 6, 1934, Serial No. 756,312

3 Claims. (Cl. 159—7)

This invention relates to egg dehydrators for dehydrating or desiccating eggs or any other more or less viscous substance, or any substance containing moisture.

5 The machine is of the class which comprises generally an endless metallic belt, means for delivering the fluid to be dried to the belt as it travels, means for heating or otherwise causing desiccation of the fluid on the belt, and means for 10 removing the finished product. The efficiency of a machine of this class depends greatly upon its ability to operate continuously and uniformly over an indefinite period of time. This is particularly true, owing to the practice of operating 15 the machine under vacuum to assist in the dehydration of the product. Whenever it is necessary to cease operation to repair, adjust or clean the machine, it is necessary to break the vacuum in the housing which encases the machine and 20 reestablish the vacuum at a considerable loss in time and energy.

The metallic belt employed travels over a pair of spaced cylindrical drums, and in the event of 25 uneven distribution of heat, which may be caused by an uneven layer of fluid on the belt or failure to remove parts of the dried product, the belt will become distorted. Upon distortion, caused by 30 irregular expansion and contraction, the belt tends to override the edges of the drums with the result that operation must be discontinued.

It is, therefore, the object of the present invention to provide an improved egg dehydrator in which the fluid to be dried is uniformly spread upon a drying belt and thoroughly cleaned therefrom at the end of a predetermined drying period; and to provide means for imparting heat to the belt uniformly throughout its entire width; and to provide means for adjusting the drums over which the belt rides, in the event of distortion, without the necessity of breaking the vacuum in which the machine operates; and to provide further novel features of construction that will promote efficient, continuous, uniform operation.

45 One form of my invention is exemplified in the accompanying drawings, to which reference is made in the following specification. In the specification further objects and advantages of the invention are made apparent.

50 In the drawings:—

Fig. 1 is a longitudinal, vertical section of an egg dehydrator constructed in accordance with my invention.

55 Fig. 2 is an enlarged view in side elevation of

the feeding apparatus illustrated in Fig. 1, showing the details of construction thereof.

Fig. 3 is a plan view of the feeding apparatus illustrated in Fig. 2.

Fig. 4 is a sectional view of the feeding apparatus, taken on line IV—IV of Fig. 3.

Fig. 5 is an enlarged view of one end of the distributing roller which forms a part of the feeding apparatus illustrated in Figs. 2, 3, and 4.

Fig. 6 is a view in side elevation of the scraping mechanism.

Fig. 7 is a plan view of the scraping mechanism illustrated in Fig. 6.

Fig. 8 is an enlarged view of the mechanism employed for maintaining the belt under tension and adjusting the tension on the belt to compensate for variations due to uneven expansion and contraction.

Fig. 9 is a sectional view, taken on the line IX—IX of Fig. 8.

20 The machine, as illustrated in the drawings, comprises an elongated housing 10 supported on leg members 11 which may be suitably secured to the floor as by pins 12 and which is insulated as shown to prevent unnecessary loss of heat. One 25 end of the housing is closed by a door 13, supported on hinges 14 and provided with a gasket 15 of rubber or other suitable gasket material for the purpose of forming an air-tight seal. A 30 caster 16 may be provided at the bottom of the door to engage the floor and partially support the weight of the door as it is swung upon its 35 hinges.

Within the housing 10 an endless metallic belt 17 is carried upon spaced cylindrical rotatable 40 drums 18 and 19. The drums are provided with outwardly extending journals 20 centrally of their ends which are received by bearings 21 and 22 so that upon rotation of the drums as they are supported by these bearings the belt may be 45 caused to travel continuously within the housing. These bearings which support the drums are mounted on an elongated frame 23 which is illustrated as formed of channel iron and which is provided with casters 24 which ride on tracks 25 supported by brackets 26 secured to the inner 50 wall of the housing.

The atmosphere within the housing is maintained at low pressure through suitable pump means (not shown) connected with pipe, such as 55 illustrated at 27, communicating with the interior of the housing so that the drying operation may take place with as little heat as necessary and without danger of cooking or burning the product being dried.

Suitable gauge means, such as illustrated at 28, may be provided for determining the condition of vacuum within the housing, and temperature, registering gauges, such as illustrated at 29 5 and 30, are provided for registering the exact temperature at various points within the machine.

The fluid that is to undergo desiccation is delivered through a pipe 31 and nozzles 32 to the feed mechanism, generally indicated at 33, by means of which it is evenly distributed upon the belt in a manner to be more fully described and carried throughout substantially the entire length of the belt in a heated atmosphere of 10 15 low pressure for a time sufficient to accomplish the desired desiccation, whereupon it is removed from the belt by scraping mechanism, generally indicated at 34, to fall against a chute 35, by means of which it is directed into a receptacle 20 24 36. The receptacle 36 may also be supported on casters 37 bearing on rails 38 to facilitate its removal from the housing when the door is opened.

In order to impart rotation to the drums which 25 carry the belt, a drive shaft 39, extending transversely of the housing, projects through one wall thereof, where it may be connected with any suitable source of power (not shown). A gear 40 is carried by this drive shaft and meshes 30 with a gear 41 secured to the drum 18, so that upon rotation of the drive shaft this drum will be caused to rotate and move the belt which will impart rotation to the other drum through frictional contact therewith. 35

During the operation of the machine, the interior of the housing may be illuminated by electric lights, such as illustrated at 42, and the process may be observed through suitable glass-covered ports, such as illustrated at 43, 40 arranged in the wall of the housing at convenient positions.

The interior of the housing may be heated by steam, hot water, electricity, or any other suitable medium, and the apparatus shown in the 45 drawings is designed for the use of steam. The main heating element comprises a stationary steam table 44 positioned directly beneath the upper flight of the belt 17. This table is provided interiorly with opposed baffles which cause 50 a more or less retarded flow of the heating medium therethrough. The top surface of the table is flat and preferably of slightly greater width than the belt which passes over the table in direct contact therewith so that the amount of 55 heat transferred to the material on the belt will be as great as possible. The direct contact between the steam table and the belt also insures equal heating of the belt throughout its width, as it eliminates the possibility of air currents between the belt and table which would interfere with the uniform heating of the belt. A similar table to that shown at 44 may also be provided directly above the lower flight of the 60 belt, as illustrated at 45.

Steam (from a source of supply not shown) is delivered through a pipe 46 which enters the housing horizontally above the belt, drops vertically downwardly, as at 47, and again passes 70 rearwardly and horizontally parallel to the axes of the drums 18 and 19. Branch lines 48 and 49 supply steam to the forward ends of the steam tables 44 and 45, which steam passes through the tables lengthwise, discharging at the opposite ends thereof through the lines 50 and 51.

to enter a main discharge line 52, by means of which the steam is carried out of the housing.

In the event that it is desired to heat the belt as it passes over the drums, I have provided means for supplying steam to the interior of 5 the drums. To accomplish this, the journals 20 of the drums are concentrically bored to permit pipes to enter the drums from the main steam supply 46. Similar discharge lines, as shown at 53 and 54, carry this steam from within 10 the drums to the main discharge line 52.

Within the drums, I provide pipes 55 which communicate with the discharge lines through a swivel joint so that they depend to a position with their lower open ends closely adjacent to 15 the lowermost part of the drums. Through this structure any condensate which forms within the drums and gathers at the bottom thereof is forced outwardly by the pressure of the incoming steam; and, furthermore, this positioning of the outlet 20 opening causes the steam to circulate and fill the entire drum rather than to pass directly through the center of the drum.

The steam supply line is provided with a union connection 56 and a similar union 57 is provided in the discharge line. Upon disconnection of the unions 56 and 57 the entire unit, including the belt, drums, feed mechanism and scraping mechanism, is free to roll out of the housing 10 on the tracks 25. Outside tracks (not shown) 30 may be positioned to receive the unit. When thus removed from the housing the unit may be thoroughly cleaned with steam under high pressure, or any other suitable cleansing medium, and the interior of the housing is also unobstructed to facilitate repairing or cleaning. When the interior of the housing is washed or steam-cleaned, the surplus moisture may be drawn off at the rear end through a pipe 58 35 which serves as a drain. 40

As previously stated, the material to be desiccated is delivered to the belt 17 in fluid or pasty form by means of the feed mechanism, generally indicated at 33, the construction of which is shown in detail in Figs. 2, 3, and 4. This feed mechanism comprises a box to which the fluid is delivered through the nozzles 32, consisting of side walls 59 and a back wall 60 positioned over the belt. The lower edges of the side walls and back wall are provided with sealing members 61 of rubber or other similar material secured to the box by means of screws, such as indicated at 62. Across the back wall of the box an angle member 63 supports downwardly extending brackets 64 which carry rollers 65 55 underlying the edges of the belt to maintain the box in close contact therewith. The belt itself forms the bottom of the box and the front wall thereof consists of a distributing drum 66. The distributing drum 66 is rotatable and, therefore, 60 can not be securely fastened to the side walls of the box, but a fluid-tight seal is produced by cutting the front ends of the side walls arcuately to fit over the heads of the drum, as shown, and by providing metal plates 67 secured to 65 the inner sides of the ends of the box and arcuately cut at their forward edges to be received in milled annular slots 68 in the heads of the drum, as illustrated in Figs. 2, 3 and 4. The said slots are of substantially the same width as 70 the metal members 67 and the close fit of these members, together with the motion due to rotation of the drum, prevents the escape of fluid at these points.

The distributing drum 66 is mounted for rota- 75

tion in conventional roller bearings 69, the housings for these bearings being formed on bearing arms 70, pivotally supported on pins 71 to permit raising and lowering of the drum to vary the thickness of the fluid spread upon the belt. Springs 72 normally urge the distributing drum toward the belt, and cams 73, fixed to a cam-actuating shaft 74, bear against the bearing arms 70 to move them against the tension of the springs 72 and thus vary the space between the drum and the belt. The cam-actuating shaft 74 extends transversely of the machine and one of its ends may be squared for the reception of a wrench to adjust the position of the cams 73. The central part of this shaft may also serve to carry a scraper blade 75, as shown in Figs. 2 and 3, for the purpose of cleaning the distributing drum as it rotates; and the tension on scraper blade may be adjusted through a crank arm 76 connected by means of a link 77 to a lever 78 on a rotatable shaft 79 (Figs. 3 and 4).

The belt 17 is maintained at a constant level directly beneath the distributing drum by means of a roller 80 carried for rotation by journals 81 in bearings 82 at its ends. The roller 80 is rotated by a chain 83 (see Fig. 1) which drives a sprocket 84 fixed to the roller shaft, which chain is driven by a sprocket 85 carried by the main drum 19. The distributing drum is rotated by a gear 86 which meshes with a gear 87 secured to the roller shaft to rotate with the roller.

It is desirable to cool the surface of the distributing drum in order to prevent the fluid from drying or coagulating as it contacts the surface of the drum. To accomplish this I have provided means for circulating cold water through the drum while the machine is in operation. The said means comprises an inlet tube 88 entering the drum axially at one end thereof and supplying water to the interior of the drum through ports 89, which water, after passing through the interior of the drum, exits through similar ports 90 and through an outlet tube 91 arranged concentrically within the tube 88 and surrounded by a sealing gasket 92 to prevent mixture of the incoming and outgoing water. The tubes 88 and 91 are, of course, non-rotatable and preferably will be carried directly outwardly through the wall of the vacuum chamber by suitable conventional connections (not shown). A rotary spring-pressed seal 93 is provided to prevent escape of the cooling water between the surfaces of the non-rotatable tube 88 and the rotatable head of the drum.

Upon operation of the machine, the fluid to be desiccated entering through the nozzles 32 is deposited in the feed box, preferably after passing over a distributing plate, such as illustrated at 94, which is provided with spaced drain lips 95. Due to the heated and partially evacuated atmosphere, this fluid, particularly if it is an egg, tends toward ebulliency and is in a more or less agitated state within the feed box. Upon coming in contact with the cooled distributing drum, the fluid is restored to a quiet state and as it is carried by the belt from the feed box under the distributing drum, this drum spreads it in an even layer, whereupon it is subjected to uniform treatment during its passage over the heated table and through the atmosphere of heat and low pressure. The temperature and pressure within the housing and the speed of travel of the belt upon which the fluid is spread are so regulated that the fluid carried by the belt will have been suitably and uniformly treated in the

period of time that is required for it to travel from the feed mechanism to the scraper mechanism, generally indicated at 34, by means of which it is removed from the belt.

This scraper mechanism is shown in detail in Figs. 6 and 7, and comprises a plurality of relatively narrow scraper blades 96 positioned side by side. Each blade is provided with an individual bearing member 97, which bearing members are supported for radial adjustment on a tube 98 so that their scraping edges may rest against the belt, as best shown in Fig. 6.

The bearing members are held against endwise movement on the tube 98 by means of a collar 99 secured to one end of said tube and a collar 100 secured to the opposite end thereof. The tube 98 is mounted for sliding movement on a rotatable bar 101 which extends transversely of the belt and is journaled in suitable bearings 102. A cylindrical cam 103, provided with a cam groove 104, is secured to the bar 101, and the collar 99 is provided with an arm 105 carrying a dog 106 which rides in the said cam groove 104. A bracket 107 is provided with a milled slot 108 which receives the lower edge of the arm 105 for sliding movement, thus preventing rotation of the tube 98. The outer end of the bar 101 is fitted with a sprocket 109, which sprocket is engaged and driven by the same chain 83 which drives the distributing drum 66, as referred to above and illustrated in Fig. 1. Upon rotation of the bar 101 the cam 103 is rotated and through engagement of the arm 105 with the cam groove 104, the tube which supports the scraper blades is caused to oscillate transversely of the belt. This oscillating movement causes the scraping edges of the blades to describe a zig-zag path on the belt, and a slicing action is produced which is considerably more effective in removing the desiccated product from the belt than is a simple scraping action.

Each scraper blade is held in contact with the belt by means of a spring 110 secured to the scraper bearing by a bolt 111 at its upper end, and fitted with an adjusting screw 112 at its lower end, which screw bears against the top surface of the blade. The tension may be simultaneously increased on all of the blades by means of a transversely extending rotatable cam bar 113 which engages the springs 110 intermediate 50 their ends. The portion of this cam bar engaging the springs is formed eccentrically with respect to the axis of rotation of the bar, so that upon rotation the pressure on the springs may be increased or decreased. The tension of the 55 springs may be varied individually and independently of the cam bar by means of the adjusting screws 112. A plurality of narrow blades, as illustrated, has been found to be most effective in removing the product from the belt, as when a 60 single blade is employed it is found that slight irregularities in the surface of the belt or the hardness of the product that is being removed will result in incomplete scraping and the building up of hard masses of the product which become 65 overcooked upon being repeatedly subjected to the drying temperature.

With the heating means and feed mechanism described above there is little opportunity for the metal belt to become distorted, due to variation 70 in temperature throughout its width. However, in the event of any such distortion I have provided means for adjusting the bearings which support the main drum 19, which means may be operated from the exterior of the housing, with- 75

out the necessity of breaking the vacuum, to counteract any tendency of the belt to override the edges of the drums. This means comprises an adjustable tension device which may be applied to either one or both of the bearings of the drum 19, and is best shown in Figs. 8 and 9.

In Fig. 9 the bearing 22 of the drum is shown as carried by a saddle 114 which is mounted for longitudinal adjustment on the channel which forms a portion of the main frame of the machine. This saddle is bored to receive slidably a longitudinally extending bar 115, threaded at one end and provided with a head 116 at its opposite end. A compression spring 117 is interposed between the head 116 and the saddle 114, and as the opposite end of the bar 115 is anchored to the frame, this spring exerts a force which tends to tighten the belt at all times. By varying the pressure on the spring 117 of one bearing, the entire drum may be thrown slightly out of line to counteract the tendency of the belt to ride off in the event of any unevenness caused by temperature variations. The threaded end of the bar 115 is anchored to the channel by a bearing member 117 secured thereto by bolts, as shown. This bearing member carries for rotation an elongated nut 119 threaded on the bar and provided at one of its ends with a bevel gear 120. The bevel gear 120 is in mesh with a second bevel gear 121 having an integrally formed trunnion supported in a bearing 122 carried by a bracket 123. This trunnion may be provided with a squared hole at its end for the reception of the squared end of a crank-shaft 124 extending outwardly through the wall of the housing through a conventional stuffing-box 125, and fitted at its outer end with a hand crank 126. Upon rotation of this crank the bevel gear 121, at its inner end, rotates the bevel gear on the nut 119, thereby feeding the rod 115 in either direction to increase or decrease the pressure on the spring 117, as desired. In order to permit this adjustment of the drum, the steam discharge line 54, illustrated in Fig. 1, is preferably made of rubber or other flexible material, so that the otherwise rigid pipe connections will not be broken due to movement of the drum.

When it is desired to remove the entire unit from the housing for cleaning, the crank shaft 124 may be pulled outwardly through its stuffing box for a distance sufficient to remove its squared end from the socket in the bevel gear 121.

While I have shown and described a specific form of my invention, it is, of course, to be understood that various changes may be resorted to in the arrangement and construction of its several parts within the spirit and scope of the appended claims.

Having described my invention, what I claim is—

1. In combination with a belt for conveying fluid matter to be dried, means for delivering such matter to the belt, a box-like structure overlying the belt at the point of delivery of matter thereto, means forming a seal between the lower edges of the box-like structure and the belt to confine the matter to the belt, a rotatable drum forming one wall of said box-like structure to evenly distribute the matter over the surface of the belt, said drum having annular grooves adjacent its ends, and means on the box-like structure fitting within said grooves to form a fluid-tight joint with the drum.

2. In combination with a belt for conveying fluid matter to be dried, means for delivering such matter to the belt, a box-like structure overlying the belt at the point of delivery of matter thereto, a rotatable drum forming one wall of said box-like structure to evenly distribute the matter over the surface of the belt, said drum having annular grooves adjacent its ends, and means on the box-like structure fitting within said grooves to form a fluid-tight joint with the drum.

3. In combination, a belt for conveying fluid matter to be dried, means for delivering said matter to the belt, a rotatable roller spaced from the belt and positioned adjacent the delivery means for causing even distribution of the matter over the surface of the belt, and means for adjusting the spacing between the roller and the belt.

CHARLES McLEAN.
